UNITED STATES PATENT OFFICE.

CHARLES C. PARKER, OF BALTIMORE, MARYLAND.

JAR-CLOSURE.

1,135,713.

Specification of Letters Patent. Patented Apr. 13, 1915.

Application filed May 8, 1914. Serial No. 837,109.

To all whom it may concern:

Be it known that I, CHARLES C. PARKER, a citizen of the United States of America, and resident of Baltimore, Maryland, have 5 invented certain Improvements in Jar-Closures, of which the following is a specification.

This invention relates to an improved closure for milk jars, formed of pulp board or 10 some analogous substance; and it consists principally, in a hollow diametrically contractible plug or stopper of peculiar construction, adapted to be forced into the throat of the jar, provided with a cap which 15 rests upon and extends over the exterior lip of the jar, as will hereinafter fully appear.

In the further description of the said invention which follows, reference is made to the accompanying drawing forming a part 20 hereof, and in which:—

Figure 1 is a vertical central section of the upper portion of a jar to which is applied the improved closure, and Fig. 2 a top view of the same. Fig. 3 is an under- 25 side view of Fig. 2, and Fig. 4 an enlarged sectional view of a part of Fig. 1.

Referring now to the the drawing, 1 represents the head of the jar, and 2 an annular projection within the throat 3 of the 30 same.

The closure consists of an inverted cup-shaped plug, the skirt *a* of which is provided with an upwardly and outwardly extending flange *b*, whereby a contractible 35 edge is produced adapted to fit closely against the under surface of the throat of the jar, combined with a cap *c* which covers the exterior lip *d* of the jar. These parts are secured together preferably by means 40 of a staple *e* as shown in the drawing.

To fully understand the advantage of a cup-shaped plug provided with an upturned flange as described, over a flat disk as a device to close the mouth or throat 3 of a jar 45 and produce a practically liquid tight joint, it must be borne in mind that a flat disk of pulp board or some similar material, has only slight diametric compressibility, and is therefore unfitted for use should the disk 50 be applied to a jar having a throat of less than the standard size.

In a cup-shaped plug its skirt *a* has a certain diametric compressibility independently of the crown *f* from which it depends, 55 and when its edge is provided with the upturned flange *b* which is susceptible to dia-

metric contraction independently of the skirt, the compressibility of the plug is much increased, and to such an extent that it is adapted as a closure for jars the throats 60 of which differ considerably in size, and a close or liquid-tight joint produced.

While a stopper constructed as described is well adapted for the purpose in view, it is desirable to stiffen the cap, and the skirt 65 of the cup-shaped plug, so that the contraction of the device in its application to jars, will be confined as much as possible to the upturned flange, in order that in the removal of the closure from a jar, the cap 70 portion of the closure will not be rendered inapplicable for reattachment to the jar should such be required, I therefore apply to the outer surface of the cup-shaped plug, a flanged reinforce 5 of the edge of the 75 flange *g* of which extends to near the junction of the upturned flange *b*, with the skirt *a* of the stopper. With the aid of this addition to the plug, the bending of the flange of the skirt takes place mainly 80 at the edge of the reinforce, and the closure can be removed from the jar without distortion of its cap element.

To effect the detachment of the closure from the jar, without distorting or breaking the cap element thereof, I provide the cap with a tongue 7 which is raised slightly as shown in Fig. 1 to admit of the insertion of the thumb nail underneath it. The space *h* produced in cutting the tongue is 90 closed in the paraffining of the closure.

It will be understood that milk jars are usually filled to the shoulder 2, and when a flat disk is employed as a closure and laid upon the said shoulder, there is no provision for the expansion of the milk should its temperature be increased, and in consequence the disk is raised from its seat and the jar thereby unsealed.

With my invention as described, the unsealing of the jar due to the cause above stated cannot take place, as the inverted cup-shaped construction of the closure provides ample space for any increase in bulk of the liquid contents of the jar.

I claim as my invention:—

1. A jar closure comprising an inverted cup-shaped plug or stopper having the skirt thereof provided with an outwardly and upwardly extending flange, adapted for insertion in the throat of the jar, combined with a cap adapted to cover the exterior

- lip of the jar, and a flanged reinforce which is secured between the crown of the stopper and the cap, with its flange in contact with the exterior surface of the skirt of the stopper.
2. A jar closure comprising an inverted cup-shaped plug or stopper having the skirt thereof provided with an outwardly and upwardly extending flange adapted for insertion in the throat of the jar, combined with a cap adapted to cover the exterior lip of the jar, and a flanged reinforce which is secured between the crown of the stopper and the cap with its flange terminating between the said upward flange of the stopper and its skirt.
3. A jar closure which consists of an inverted cup-shaped plug or stopper having the skirt thereof provided with an outwardly and upwardly extending continuous or unbroken flange which produces a contractible circular edge adapted to come in contact with the inner surface of the throat of a jar, combined with a cap adapt-

ed to cover the exterior lip of the jar, and to which the stopper is secured, a reinforce interposed between the cap and the plug, and a tongue formed in the cap, by cutting through the same down to the surface of the reinforce beneath.

4. A jar closure which consists of an inverted cup-shaped plug or stopper having the skirt thereof provided with an outwardly and upwardly extending continuous or unbroken flange which produces a contractible circular edge adapted to come in contact with the inner surface of the throat of a jar, combined with a cap adapted to cover the exterior lip of the jar, and to which the stopper is secured, an imperforate reinforce interposed between the cap and the plug, and a tongue formed in the cap, by cutting through the same down to the surface of the reinforce.

CHARLES C. PARKER.
